UNITED STATES PATENT OFFICE.

JAMES W. PATCH, OF FORT WAYNE, INDIANA, ASSIGNOR TO GENERAL ELECTRIC COMPANY, A CORPORATION OF NEW YORK.

CASING FOR ELECTRICAL APPARATUS.

Application filed November 16, 1920. Serial No. 424,488.

To all whom it may concern:

Be it known that I, JAMES W. PATCH, a citizen of the United States, residing at Fort Wayne, county of Allen, State of Indiana, have invented certain new and useful Improvements in Casings for Electrical Apparatus, of which the following is a specification.

My invention relates to casings for electrical apparatus submerged in oil, such as 10 transformers and the like.

More specifically my invention relates to casings provided with deep corrugations in its side walls in order to increase the cooling capacity of so-called "self-cooled" apparatus.

The object of my invention is to provide an improved arrangement of parts which may be readily and economically manufactured.

The load which may be safely carried by any piece of electrical apparatus is determined by its ability to dissipate properly the heat generated while performing under 25 load. This is particularly true of oil submerged electrical apparatus such as transformers. In the so-called "self-cooled" variety, which depends mainly on radiation to the surrounding medium or atmosphere to 30 effect the necessary cooling, various forms of external radiators have been used to increase the radiating surface and thereby increase the rating of the apparatus.

Another and cheaper way for increasing 35 the radiating surface of the casing for electrical apparatus is to provide the side walls of the casing with corrugations, an advantageous form of such corrugations being disclosed in U. S. Letters Patent to Moody, 40 No. 713,901. Much difficulty however has been experienced in providing deep corrugations for apparatus of large capacity in a cheap and efficient manner; such corrugations are generally required to be six, 45 eight or more inches deep.

In accomplishing the object of my invention I employ corrugated units composed of a plurality of convolutions, such units having a special development of a character to 50 provide guides for bending. They may also at the same time provide knobs of surplus stock for welding purposes. These units when bent up have end portions lying in a plane and are adapted to be assembled upon 55 top and bottom rings to form a casing, the

same being braced and reinforced in a novel manner, as will hereinafter appear.

For a more complete understanding of the nature and objects of my invention reference should be had to the following detailed description taken in connection with the accompanying drawing in which:

Fig. 1 is a view in front elevation of the top portion of a corrugated unit from which to construct casings for electrical apparatus according to my invention; Fig. 2 is a top plan view of the corrugated unit shown in Fig. 1; Fig. 3 is a fragmentary view of the plane development of an end of my unit; while Fig. 4 is a fragmentary view mainly 70 in vertical section of a casing constructed in accordance with my invention.

Referring now to the drawing, 10 denotes a unit of my invention shown in perspective as bent to the desired form and lying on a 75 surface slightly curved.

This unit is shown as having four convolutions and is made by bending up a piece of sheared stock 11 developed as shown in Fig. 3 which has ends provided with V shaped notches 12, likewise four in number to provide the four convolutions in the formed unit. Between the V shaped notches the stock is cut out to provide a back, the same being preferably more deeply cut out 80 at each side in order to leave a knob or protruding portion as shown at 13. Each edge of the sheared blank formed as shown in Fig. 3 is cut to provide the development of half a back along the edge plus a portion 85 adapted to be bent up to provide an upstanding welding edge. The welding edges are adapted to be bent up sharply along the dotted lines 14, the convolution as a being similarly bent up from such edge along the dotted line indicated at 15. The crest of the corrugation is formed by bending along the dotted line 16 which extends from the bottom of a V notch at the top of the blank to the bottom of one at the lower end, the bending of course on the line 16 being in an 90 opposite direction to that along lines 14 and 15 and not very sharp. The other backs are formed by bending along the lines indicated at 15'.

Units when thus bent along the longitudinal lines 14, 15, 16, etc., are ready to have the ends of the convolutions closed. These ends may be closed by any suitable drawing and pinching device which provides offset 105 110

edges, as shown at 20, that may be closed by welding, brazing and the like.

Units with ends closed and finished in this manner are adapted to be united to one another by welding along their upstanding longitudinal edges shown at 21.

A sufficient number of units having been united in this manner to provide a tank of the desired perimeter, they are ready to be 10 assembled on top and bottom rings 30 and 31 to form a tank as shown in Fig. 4. The development shown in Fig. 3 is adapted to provide a corrugated unit, when bent as 15 shown in Figs. 1 and 2, which will have its backs and ends lying in a ruled or smooth surface. The now serrated ends of the formed unit 10 will consequently fit snugly against the curved surfaces (which are one species of ruled surface) of the top and 20 bottom rings 30 and 31.

In welding the formed units to the rings 30 and 31 the knobs 13 become fused and provide an excess of metal which may be flowed about the weld as needed. This is 25 particularly advantageous when welding thin metal such as that of which the formed units are made, while relatively thick metal is employed in the rings 30 and 31. This mode of welding produces welds along zig-zag lines about the top and bottom rings, 30 as the welds are made up over the abutting portions of the convolutions where they join the rings and then down across the ends of the back portions about the knobs 13. These 35 zig-zag welds brace the units welded to the rings 30 and 31 and prevent them from being easily pried loose from these rings.

The rings 30 and 31 are further braced and reinforced by the provision of inwardly projecting stiffening ribs 32, which may be provided by welding an angle iron about the interior peripheries as shown.

Tank bodies formed of corrugated units 10 and top and bottom rings 30 and 31, as 40 just described, are then ready to be welded or otherwise secured to suitable bases, such as that shown at 35; the tops being closed by suitable covers which are not shown.

While I have called the members 30 and 31 50 "rings" in the above, it will be understood that they need not be circular, but may be oval, elliptical or other suitable shape.

Having now described an embodiment of my invention which is at present the best 55 means known to me for carrying the same into effect, I would have it understood that this is merely illustrative and that I do not mean to be limited thereby to the precise details shown, nor restricted in the choice of 60 65 recognized equivalents except as defined in my claims hereunto annexed.

What I claim as new and desire to secure by Letters Patent of the United States, is:

1. A sheet metal casing for electrical apparatus comprising top and bottom rings

and corrugated walls secured therebetween; said walls being composed of units having alternate convolutions and flat backs, said convolutions having closed ends, the units being formed to lie in a ruled surface and 70 to have serrated welding edges at their ends.

2. A sheet metal casing for electrical apparatus comprising top and bottom rings and corrugated walls secured therebetween: 75 said walls being composed of units made from sheared blanks and formed by bending along parallel longitudinal lines to provide alternate convolutions and flat backs to lie in a ruled surface, said convolutions being drawn together at their ends to close the 80 same and formed to provide zig-zag welding edges at the ends of the units.

3. A sheet metal casing for electrical apparatus comprising top and bottom rings and corrugated walls secured therebetween; said 85 walls being composed of units made from sheared blanks having ends formed with a plurality of spaced V shaped notches, adjacent V shaped notches being separated by an intervening projecting knob, the blank 90 being bent along parallel longitudinal lines to provide flat backs and a plurality of convolutions lying in a ruled surface, said convolutions being drawn together at their ends to close the same.

4. A sheet metal casing for electrical apparatus comprising top and bottom rings and corrugated walls secured therebetween; said rings being provided with stiffening ribs and 100 having said walls welded thereto along zig-zag paths.

5. A sheet metal casing for electrical apparatus comprising top and bottom rings and corrugated walls secured therebetween; said 105 rings having angle irons welded interiorly about their peripheries to provide stiffening ribs therefor and having said walls welded thereto exteriorly along zig-zag paths.

6. A sheet metal casing for electrical apparatus comprising top and bottom rings and corrugated walls secured therebetween; said 110 rings being provided with stiffening ribs interiorly and having said walls composed of units with serrated ends welded thereto exteriorly along paths following the serrated 115 ends of said units.

7. A sheet metal casing for electrical apparatus comprising top and bottom rings and corrugated walls secured therebetween; said 120 walls being composed of units having a plurality of spaced convolutions, the material of the units between adjacent convolutions being extended to form projecting flat knobs, whereby said walls have serrated end edges, the walls being welded to said rings 125 along paths following said serrated end edges.

In witness whereof, I have hereunto set my hand this 12th day of November, 1920.

JAMES W. PATCH.
